UNITED STATES PATENT OFFICE.

DANIEL STEWART BIRRELL AND GEORGE SMITH, OF WARRINGTON, ENGLAND.

WEAVING OF CRIMPED OR WIRE-MESH WORK MATERIAL.

1,311,746.

Specification of Letters Patent. Patented July 29, 1919.

Application filed June 7, 1918. Serial No. 238,763.

To all whom it may concern:

Be it known that we, DANIEL STEWART BIRRELL and GEORGE SMITH, subjects of the King of England, and residing at Warrington, in the county of Lancaster, England, have invented Improvements in and Connected with the Weaving of Crimped or Wire-Mesh Work Material, of which the following is a specification.

10 This invention has reference to weaving or manufacturing crimped or waved wire mesh work material or fabric, and it has primarily for its object to provide improvements in connection with such manufacture 15 so as to enable it to be done by machinery, at least to a large extent.

Hitherto the rate of manufacture of mesh work fabric of crimped or waved wire, consisting of longitudinal or warp wires, and 20 separate lengths of wefts or transverse wires, has been very slow owing to certain difficulties and defects in the wires and other conditions; and moreover, the product has not been uniform, even with the slow 25 rate of progress or manufacture which has taken place. This slowness is due partly to attempts by the operators to correct inaccuracies of manufacture, and to make the mesh work approach uniformity and a true 30 geometrical pattern.

Further, in making mesh work of crimped or wave wires, say of one, two or more crimps or waves between each intersection or cross laying of mesh wires, it is found 35 in practice that the pitch of the waves or crimps in the lengths of wires, although made in the one machine, varies, due to variation of quality or temper of the metal wires, and other causes, and consequently 40 in making up mesh work of these wires, as in the warp wires the crimps do not come true, or coincide transversely, generally, a defective material is produced.

The difficulties and drawbacks hitherto 45 existing are by this invention overcome, and the production of a continuous fabric of the character referred to, of a uniform character and true geometrical design or pattern of fabric, is effected by mechanical 50 means, in which the wires are mechanically adjusted, and irregularities of pattern, and inequalities of pitch of the crimps or waves are adjusted or corrected and gaged, and a flat and even and uniform fabric of the 55 required geometrical design and formation

of mesh, is accomplished; and according to this invention, as the fabric is being made, the crimps or waves in this multiplicity of warp wires, will be caused in the manner hereinafter described, to come in the true 60 position transversely, and so that the weft or transverse waved wires, which are introduced between the warp wires when the shed is formed, by a suitable shedding mechanism, will lie truly in position, and 65 can be beaten up by a slay to this true position; and the means and mechanism employed constitute a correcting and gaging mechanism, and general means of manufacturing this mesh work mechanically, rapidly, 70 of uniform structure, and efficiently.

The mechanism for adjusting, setting and correcting wires and meshes, and forming a true gage, consists of tapered or conical gages which are inserted through the meshes 75 between the longitudinal and transverse wires forming them, and at one part, which is to form the gaging part, they are of the size of mesh required, and they are inserted through the meshes mechanically. In the 80 preferred form they are formed as teeth on the periphery of wheels or disks suitably carried on a shaft transversely in the bed or table of the machine, along the surface of which the fabric is moved; and they are 85 rotated mechanically, and in and by their motion, they not only adjust and correct the positions of both sets of wires (warp or weft) in the piece, but also move the fabric along the table, thrusting it forward. In 90 front of and behind these devices is a roller, say a weighted or spring pressed roller, which presses and holds the material down onto the face of the table, and assists in the action of the adjusting or gaging wheels, 95 and the general manufacture, which wheels both push the fabric forward, as well as draw the warp wires along through the shedding machinery from the warp roller.

By correcting the lengths of wire and 100 obtaining a true crimp pitch, these crimps will come in the correct position transversely for the weft wires, which will be introduced through the shed and beaten up by the slay; and afterward when the 105 meshes thus formed come under the action of the gages or correcting devices, if any irregularity of mesh exists, it is again corrected, so that the gages or correcting devices correct any defects at the point where 110

the slay knocks up the weft wires, and again at the gages.

The gages or correcting devices on the wheels or disks will, at their bases, be close together, that is the space between them will be just sufficient to enable the weft wires to lie in them, when the teeth rise to the uppermost position, so that they act as cog wheels to the fabric.

10 The invention is illustrated in the accompanying drawings, in which Figure 1 is a longitudinal view of the apparatus or machinery employed, and Fig. 2 is a plan of same.

15 Fig. 3 is a longitudinal section showing a detail of the mesh adjusting and correcting or gaging apparatus or means; and Fig. 4 is a transverse view of a part of same to a smaller scale.

20 In the drawings, 1 are the crimped or waved warp wires which are wound and carried on a warp reel 3, and 2 are the crimped or waved weft wires which are made in suitable lengths, and generally 25 introduced by hand into the shed of the warps. 4 are the shed forming heddles which are adapted to be operated say by foot, in the well-known way; and 5 is the slay for beating up the weft wires 2, it being

30 operated by hand, by a handle 6.

The adjusting or correcting gages are marked 10, and in the case shown they are provided upon wheels or disks 11, and form a species of tooth wheel; and as will be seen 35 more clearly in Fig. 3, the gages lie closely together at their bases, the spaces between them being just sufficient to enable the weft wires 2, to lie in the hollow at their roots.

In the case shown, there are two sets of 40 these gage or correcting disks or wheels 11, one below and one above the fabric. They are mounted on rectangular shafts 13, upon which they are threaded, and are held in position therein in any suitable way. The 45 wheels are thus readily changeable, and by changing them and putting on wheels having teeth or gages of the size of gage required, any size of mesh fabric can be made in the machine.

50 The two shafts 13 are geared together by tooth wheels 14, and are driven as herein-after described.

The gage or correcting wheels 11 of the lower and upper set, are disposed in planes 55 intermediate one another, see Fig. 4, and the gage teeth of each set only enter every alternate mesh of the fabric, but the two together enter every mesh. The teeth of the two sets of gage wheels overlap, but the 60 gap between them at the bases of the two sets, lie respectively below the position of the warp wires 2, and above same; and in these gaps the warps lie in passing over the table 18 of the machine.

65 In front of and beyond the gage wheels

11, are the pressing rollers 15, 16 which are free to rise in their bearings 17; and they are of considerable weight, that is such that they exert considerable downward pressure upon the material, as to hold it in position and flat on the table 18, in front and at the back of the gaging wheels 11; and they promote or assist materially and generally, by their coaction and effect with the wheels 11, in the accomplishment of the object of the invention, namely, an improved machine made crimped or waved wire mesh work fabric.

In the machine shown, the rotation of the gage or correcting wheels 11 is effected by a lever and pawl and ratchet arrangement 20 acting on one of the shafts of the wheels 11, and it is adapted to be worked by hand, and by the same attendant who works the heddles 4; but if desired, it may be worked by 85 machinery in a mechanical driven machine.

By the operation of these wheels 11, the setting or adjusting and correcting and gaging of the meshes of the wires constituting the fabric, so as to produce a true rectangular mesh article, is accomplished; and the warp wires from the drum 3 are pulled forward, and the finished fabric pushed forward to the taking on drum, not shown.

As the weft wires are introduced through 95 the shed, between the slay 5 and the front roller 15, they are beaten up by the slay by the operator into the position required, approximately, and any inaccuracy of position, or want of truth of the wefts, is corrected by the gages 10 as hereinabove described; and at the same time any inaccuracies of position of the warp wires are corrected by the gage teeth 10.

In the manufacture of fabric of the character referred to, it has not hitherto been found possible or feasible, commercially, to make it of long lengths, such as several hundred feet long, a feasible limit being between 50 and 100 feet, as with greater 100 lengths than this, the fabric has been found to become ragged, and unmanageable at the end of this relatively short length; whereas by the method of operating upon the wires mechanically as described, any length of 110 uniform structure can be made, and made rapidly and inexpensively; and as above stated by this invention, although the pitch of the crimps in all the wires used may be not regular and uniform, the system and 115 machine will obviate the effect of same, which otherwise would take place through such defects; and in addition to the effects or advantages above referred to, the machine is self-starting, and no pulling 120 through of the fabric is required, and it does 125 away with scrap ends of wire, and so saves wire, there being no tag ends.

What is claimed is:—

1. In a machine for weaving crimped or 130

- waved wire mesh-work material or fabric, gaging means comprising upper and lower rotatable elements embodying annular sets of tapered teeth to enter the meshes of the 5 fabric, said annular sets of teeth having spaces at the roots of the teeth for receiving the weft of the fabric.
2. In a machine for weaving crimped or waved wire mesh-work material or fabric, 10 gaging means adapted to enter all the meshes of the fabric and to adjust and gage the wires and correct inequalities of pitch of same, and pressure means engaging the fabric upon the sides of the gaging means.
- 15 3. In a machine for weaving crimped or waved wire mesh-work material or fabric apparatus for adjusting setting and correcting all the wires and meshes, gaging means consisting of tapered or conical teeth around 20 the periphery of a wheel adapted to pass through the meshes mechanically, and at the part forming the gaging portion are of the size of the mesh required, and at their roots

or bases have spaces between them just sufficient to enable the weft to lie in same. 25

4. In a machine for weaving crimped or waved wire mesh-work material or fabric, the combination of two sets of gage wheels adapted to enter and gage all the meshes one below and one above the fabric, disposed 30 in planes intermediate one another and means for rotating same.

5. In a machine for weaving crimped or waved wire mesh-work material or fabric, the combination of rotatable gage wheels 35 adapted to pass through the meshes of the fabric, and pressing rollers disposed one in front of and one behind said wheels.

In testimony whereof we have signed our names to this specification in the presence 40 of two subscribing witnesses.

DANIEL STEWART BIRRELL.
GEORGE SMITH.
